UNITED STATES PATENT OFFICE.

EUGENE W. VOGEL, OF OAK PARK, ILLINOIS, ASSIGNOR TO CHICAGO RAILWAY SIGNAL & SUPPLY COMPANY, OF CARPENTERSVILLE, ILLINOIS, A CORPORATION OF ILLINOIS.

GUIDE-BRACKET FOR DETECTOR-BARS.

1,229,828.

Specification of Letters Patent. Patented June 12, 1917.

Application filed October 5, 1916. Serial No. 123,806.

To all whom it may concern:

Be it known that I, EUGENE W. VOGEL, citizen of the United States, residing at Oak Park, in the county of Cook and State 5 of Illinois, have invented certain new and useful Improvements in Guide-Brackets for Detector-Bars, of which the following is a specification.

My invention relates to detector bars employed in connection with railroad switches for the purpose of preventing such switches from being inadvertently thrown at improper times, for example, when a train is passing over the switch.

15 The invention has reference more particularly to a detector bar of the type employing a cam or plate with an inclined lower edge for raising the bar above the top of the rail, when the bar is moved longitudinally, and the object of the invention is to provide an improved guide bracket or clip adapted to be attached to the rail and provided with a roller over which the cam plate on the detector bar rides when the 20 bar is moved. The guide bracket of my invention is superior to devices of this type now in use in that friction is minimized, clogging of the roller avoided, and lubrication made convenient and easy. The construction also has the advantage that the 25 roller is capable of being readily removed from the bracket when worn and requiring replacement. The device is also strong, durable and inexpensive to manufacture.

30 35 The invention is illustrated, in a preferred embodiment, in the accompanying drawing wherein—

Figure 1 is a side elevation of a rail provided with a detector bar and with the guide bracket of my invention.

Fig. 2 is a sectional view on line 2—2 of Fig. 1.

40 Corresponding parts are designated by the same reference characters in both figures.

The rail is shown at A. B is the detector bar, and C one of the cam plates secured to the bar, for example, by rivets D. The cam plate is formed with inclined lower 45 edges E.

The detector bar is supported and guided in a position alongside of the rail by a guide bracket which may be clipped to the base of the rail or may be bolted through 50 the vertical web thereof. I have shown the

bracket, designated as a whole by the letter F, as clipped to the base of the rail but provided with bolt holes so that if desired it may be bolted to the web. The guide bracket comprises a base portion G 60 which lies upon the base flange H of the rail and is provided with a jaw I extending around and under one edge of the base flange through which extend bolts J threaded at one end for nuts K and formed 65 at their opposite extremities with hooks L extending around the opposite edge of the base flange of the rail from that engaged by jaw I. Extending upwardly from the base portion G is a web M preferably 70 formed with bolt holes N, so that the device may, if desired, be bolted to the vertical web O of the rail, the web M having a lip P extending under and around the lower portion of the head Q of the rail. At the outer edge of the base portion G is an upstanding web R formed with a lip S which lies close to the cam plate C of the detector bar B. T is a roller formed with gudgeons U of considerably smaller 80 diameter than the roller. The roller gudgeons extend in and find bearings in the bottom of slots V, W, slot V being formed in web R and slot W in a projection X on web M. 85

When the detector bar is moved longitudinally from right to left, Fig. 1, the cam surface E adjacent the roller rides up on the roller, raising the detector bar to the dotted line position of Fig. 2. The roller 90 is stronger, more durable and moves with less friction than the corresponding element in constructions employing a bolt and sleeve to support the detector bar in the bracket. Moreover, the gudgeons or journals of the roller are easily lubricated. By 95 raising the detector bar the roller may be removed from the bracket if occasion requires it.

I claim:

1. The combination with a rail, detector bar and cam plate secured to the bar, of a roller to support the bar and coöperate with the cam plate to raise the bar when moved longitudinally, which roller is provided with journals at opposite ends, and a guide bracket provided with means for attaching it to the rail and formed with bearings for the roller journals. 105

2. The combination with a rail, detector 110

bar and cam plate secured to the bar, of a roller to support the bar and coöperate with the cam plate to raise the bar when moved longitudinally, which roller is provided at 5 opposite ends with integrally formed journals of smaller diameter than the roller, and a guide bracket provided with means for attaching it to the rail and formed with oppositely arranged upstanding webs slotted to provide bearings for the roller journals, permitting the roller to be removed from the bracket when the detector bar is raised.

3. The combination with a rail detector 15 bar and cam plate secured to the bar, of a guide bracket for the bar adapted to be secured to the rail and comprising a base portion, a web which lies alongside of the vertical web of the rail and is provided with 20 an outward projection formed with a bearing recess open at the top, and an upstanding web terminating in a guide lip extend-

ing close to the cam plate of the detector bar and formed with a bearing recess, and a roller to coöperate with said cam plate 25 formed with integral journals, of smaller diameter than the roller, adapted to extend into the aforesaid bearing recesses.

4. The combination with a rail detector bar and cam plate secured to the bar, of a 30 guide bracket for the bar comprising a base portion, a jaw adapted to fit over one edge of the rail base, a web which lies alongside of the vertical web of the rail and adapted to be secured thereto and formed with an 35 outward projection formed with a bearing recess open at the top, and an upstanding web terminating in a guide lip extending close to the cam plate of the detector bar and formed with a bearing recess, and a 40 roller to coöperate with said cam plate formed with integral journals adapted to extend into the aforesaid bearing recesses.

EUGENE W. VOGEL.
